United States Patent

Des. 239,929
Patented May 18, 1976

239,929

TRUCK BODY

Lloyd J. Hawkins, 14922 Coldwater Road,
Fort Wayne, Ind. 46825

Filed Nov. 15, 1974, Ser. No. 524,206

Term of patent 14 years

Int. Cl. D12—08

U.S. Cl. D12—98

FIG. 1.

FIG. 2.

FIG. 3.

FIG. 4.

FIG. 1 is a perspective view of a truck body showing my new design;

FIG. 2 is a side elevational view thereof opposite to the side shown in FIG. 1 on a reduced scale;

FIG. 3 is an end elevational view thereof opposite to the end shown in FIG. 1 on a reduced scale; and

FIG. 4 is a bottom plan view thereof on a reduced scale.

I claim:

The ornamental design for a truck body, as shown.
